UNITED STATES PATENT OFFICE.

OMAR STEVENS AND MANFORD A. STEVENS, OF NEW SALEM, INDIANA.

GATE.

SPECIFICATION forming part of Letters Patent No. 678,797, dated July 16, 1901.

Application filed March 30, 1901. Serial No. 53,704. (No model.)

To all whom it may concern:

Be it known that we, OMAR STEVENS and MANFORD A. STEVENS, citizens of the United States, residing at New Salem, in the county 5 of Rush and State of Indiana, have invented certain new and useful Improvements in Gates, of which the following is a specification.

This invention relates to improvements in 10 gates for driveways; and the object is to provide means whereby the gate can be opened and closed by a person on horseback or in a vehicle without dismounting or alighting from the vehicle.

15 The object also is to provide a construction that will be well supported without the necessity of setting the gate-post in the ground, where it will rot off and destroy the support of the gate.

20 The object also is to provide an opening and closing mechanism that will consist of few parts which operate in a simple and positive manner and which will be wholly above ground, out of danger of being covered with 25 water and frozen up in cold weather.

We accomplish the objects of the invention by the mechanism illustrated in the accompanying drawings, in which—

30 Figure 1 is a perspective view of a gate having our improvements, the view showing the gate in full lines in closed position; and Fig. 2 is a detail showing the gate partly open.

Like letters of reference indicate like parts throughout both views of the drawings.

35 The gate A is hinged to a frame of which B is the principal post, C an auxiliary post farther down the fence-line, and D a third post set at one side of the other two. The three posts are connected by the horizontal 40 timbers E E' E'', placed upon the ground and forming a foundation or base to support the posts, which latter need not and preferably will not be set in the ground.

The posts B and D are connected by the 45 cylindrical tube F, which preferably will be a piece of gas-pipe, the ends of which are inserted in round holes in the said two posts and form a hinge for the gate A, the corner of which gate is fastened to said tube F.

50 This hinge allows the gate to swing up in a

vertical plane into the open position. (Shown in dotted lines in Fig. 1.)

Pivotedly secured to the top of the post C is the lever G, the inner end of which lever is connected by the chain g with the lower 55 bar of the gate A at a point suitably remote from the hinged corner to give a sufficient leverage. The opposite and outer end of the lever G is provided with the weight g', which can be adjusted on the lever to a position in 60 which it will nearly but not quite counter-balance the closed gate. It is apparent that it will take more power to start the gate up and move it through the first stages of its opening than will be subsequently required, 65 and inasmuch as the weight g' on lever G nearly but not quite balances the gate in the closed position of the latter we provide means by which the deficiency will be supplied by a lift on the gate administered by 70 the person desiring to open same in order to pass through. This is supplied by attaching a cable H to the top of the gate between its ends, passing the cable up over a pulley h, supported from the top of the post B, and 75 thence over the pulley i, supported by post I, standing by the roadside a suitable distance away from the gate. The end of the cable hangs down from pulley i in easy reach and is provided with the handle j. 80

Inasmuch as the gate must be closed as well as opened by persons approaching from either side, we duplicate the cable-pulleys and posts, as shown at H', (the pulley h' mounted by the side of pulley h on same shaft,) 85 pulley i' and post I', and handle j'. The person desiring to pass the gate will ride up to post I or I' and pull down on handle j or j', as the case may be, and raise the gate by the cable to about the position shown in Fig. 2, when 90 the weight on the lever G will be able to exert sufficient force to continue to raise the gate and carry it past its point of equilibrium. Then in order to keep the gate from striking the base-frame connecting the posts with too 95 much force by its momentum in opening and also to nearly counterbalance the opened gate, whereby it will be sensitive to a reasonable force in closing, we provide the arm G' on lever G and connect the outer end of said 100

arm by chain g'' with the adjacent end of the gate, as shown. In the operation of opening after the gate has passed a certain position the chain g becomes slack and the chain g'' 5 taut, and in closing the gate the same cords which lifted the gate to open it will start the gate to close by pulling the vertical or raised gate back toward its lowered position. Hence the person passing along the driveway will 10 pull down on the first handle, as i , that he comes to to open the gate and after passing through will pull down on the handle, as i' , on the other side to close the gate.

It will be noted that the cables H and H' 15 are fastened to bars l instead of directly to the frame of gate. The purpose of this is to cause the pull on the cables to automatically open a fastening by which the closed gate is latched. The bar l is a lever pivotally secured 20 to the top rail of the gate. It is connected by cord m with the bar n , pivoted to the front end bar of the gate. This bar n by its weight drops out against the post P and its outer end enters a notch p in said post, which locks the 25 gate against any upward movement of the latter until the end of the bar is first swung back out of the notch. A pull on the handles i or i' will draw the bar n out of the notch in the post P the first thing.

30 Having thus fully described our invention, what we claim as new, and wish to secure by Letters Patent of the United States, is—

1. A gate pivoted at one corner to swing in a vertical plane, a lever connected on one 35 side of its pivot by a flexible connection with the lower side of the gate, and by a flexible connection from the end of the gate to the same arm of the lever, nearer the pivot, a weight on the other side of the pivot nearly 40 balancing the gate, and a cord connected with

the gate, pulleys over which the cord is passed and a hand-pull to which the cord is fastened, substantially as described and shown.

2. A gate pivoted to swing in a vertical plane about one of its corners, a separately- 45 pivoted lever, a flexible connection between one end of the lever and the lower end of the gate, a lateral arm on the lever between the said flexible connection and the pivot, flexible connection of the outer end of the arm 50 and the adjacent end of the gate, a weight on the end of the lever on the other side of the pivot from the end of the lever having the arm, and a cord fastened to the upper side of the gate, and passing over pulleys 55 connected with hand-pulls on either side of the gate, substantially as described and shown.

3. A gate pivotally secured at one of its lower corners, a weighted and pivoted lever 60 having double flexible connection with the lower side and end, respectively, of the gate, a notched post at the free end of the gate, a bar pivoted to the gate and adapted to drop by gravity into the notch in the post, a bar 65 pivoted to the top of the gate and connected with the first-mentioned bar, cords connected with the second bar, pulleys over which the cords pass and hand-pulls terminating the cords, all substantially as described and 70 shown.

In witness whereof we have hereunto set our hands and seals at Indianapolis, Indiana, this 9th day of February, A. D. 1901.
